Amelia and Russell, his Atlys

UNITED STATES PATENT OFFICE.

GEORGE HUNTER, OF ELGIN, ASSIGNOR TO THE ELGIN NATIONAL WATCH COMPANY, OF CHICAGO, ILLINOIS.

WATCH-DIAL.

SPECIFICATION forming part of Letters Patent No. 340,507, dated April 20, 1886.

Application filed December 11, 1883. Serial No. 114,192. (No model.)

To all whom it may concern:

Be it known that I, GEORGE HUNTER, of Elgin, in the county of Kane, and in the State of Illinois, have invented certain new and useful Improvements in Watch-Dials; and I do hereby declare that the following is a full, clear, and exact description thereof, reference being had to the accompanying drawing, making a part of this specification, in which is shown my improved dial separate from a watch.

My improvement relates to the noting of time by the new style, in which one series of consecutive numbers is employed; and it consists, principally, in a dial having the circle of twenty-four consecutive hour-numbers arranged upon a uniform background with the number 12 at the top and the number 24 at the bottom of the dial, and the space within the circle of numbers of which the lower portion is dark or cloudy and the upper portion is light, substantially as hereinafter shown.

It consists, further, in a dial having the circle of twenty-four consecutive hour-numbers arranged with the number 12 at the top and the number 24 at the bottom of the dial, and the space within the circle of numbers made cloudy over its lower portion and on its upper portion made light and provided with the representation of rays of light radiating downward from below the twelve or noon mark, substantially as hereinafter described.

In the annexed drawing, A represents a watch-dial, which near its periphery is provided with a circle of divisions, a , to indicate seconds within the same, has a second circle, a' , of divisions to indicate minutes, and within said latter has a third circle, a'' , that is divided into twenty-four spaces, each of which 40 denotes an hour of time. Said hours are consecutively numbered from 1 to 24, and the numbers are arranged so that 12 is at the upper center of the circle and 24 is at the lower center of the same. The lower portion of the 45 circular space a'' , inclosed by the hour-num-

bers, is dark and cloudy, while its upper portion is light, and within the latter is a word or symbol—preferably the name or mark of the watch, or the name or trade-mark of the maker. Rays of light are represented as radiating 5c downward from the part of the dial-space directly below the twelve-hour or noon mark, thus indicating the position of the sun at noon. The space a'' thus ornamented represents light and darkness, and as the former is adjacent to 55 the hour-numbers, which cover the day, and the dark portion of said space comes opposite to the numbers which designate the night hours, the user is caused to associate with the hour-numbers the adjacent design and to unconsciously class them accordingly. 60

Having thus fully set forth the nature and merits of my invention, what I claim as new is—

1. A dial having the circle of twenty-four 65 consecutive hour-numbers arranged upon a uniform background, with the number 12 at the top and the number 24 at the bottom of the dial, and the space within the circle of numbers, of which the lower portion is dark 70 or cloudy and the upper portion is light, substantially as shown.

2. A dial having the circle of twenty-four consecutive hour-numbers arranged with the number 12 at the top and the number 24 at the 75 bottom of the dial, and the space within the circle of numbers made cloudy over its lower portion and on its upper portion made light, and provided with the representation of rays of light radiating downward from below the 80 twelve or noon mark, substantially as described.

In testimony that I claim the foregoing I have hereunto set my hand this 5th day of December, 1883.

GEORGE HUNTER.
